UNITED STATES PATENT OFFICE

AMABLE CHARLEBOIS, OF FERNDALE, MICHIGAN

WINDOW CONSTRUCTION

Application filed May 28, 1927. Serial No. 194,929.

This invention relates to a door or window construction wherein the door or window frames are slidable between horizontal rails and are adapted to close a large door or window opening, irrespective of where the opening may be in a building.

The primary object of my invention is to provide slidable door and window frames especially designed for leaded lights which 10 lend weight to such frames, and the frames have been constructed so that the lights can be easily and quickly installed together with means for insuring easy adjustment of the door or window frames.

15 A further object of my invention is to furnish door or window frames with meeting rails that insure a tight connection at the juncture of said frames when closed, and outer rails of the frames are provided with 20 weather strips to exclude the elements adjacent said rails.

The above are a few of the objects attained by the simple and durable construction to be hereinafter specifically described 25 and then claimed, and reference will now be had to the drawings, wherein

Figure 1 is a front elevation of a portion of a building provided with doors or windows in accordance with this invention;

30 Fig. 2 is a horizontal sectional view taken on the line II—II of Fig. 1;

Fig. 3 is an enlarged horizontal sectional view taken on the line III—III of Fig. 1, showing a weather strip;

35 Fig. 4 is an enlarged vertical cross sectional view of a lintel provided with a top rail;

Fig. 5 is a similar view of a sill provided with a bottom rail, and

40 Fig. 6 is an enlarged horizontal sectional view of the meeting rails of the door or window frames.

In the drawing, the reference numeral 1 denotes a building structure including a door 45 or window lintel 2 and a sill 3. The lintel and sill are connected by stiles 4.

Extending longitudinally of the lintel 2 and the sill 3 are top and bottom guide rails 5 and 6 respectively. These rails are angular 50 in cross section, may be secured in place by

screws or other fastening means 7, and are of greater length than the lintel or sill so that the ends thereof may enter door or window wells 8 in the structure 1.

Slidable between the guide rails 5 and 6 are door or window frames preferably made of metal and identical in construction, therefore I deem it only necessary to consider one of the frames, which is composed of a top rail 9, a meeting rail 10, an outer rail 11 and a sectional bottom rail 12. The top rail 9 is substantially H-shaped in cross section so as to provide a channel 13 to receive the top guide rail 5 and a channel to receive a light 14. The meeting rail 10 and the outer rail 11 are spot welded or otherwise connected to the top rail 9, and said meeting and outer rails have the confronting edges thereof provided with channels 15 to receive the side edges of the light 14.

The sectional bottom rail 12 is composed of two flat bars maintained in spaced relation by rollers or wheels 16 rotatable on screws or transverse members 17 connecting the parallel bars, said bars forming a channel to receive the bottom guide rail 6 so that the rollers or wheels may travel on the guide rail. The bottom rail 12 also affords a channel for the lower edge of the light 14 and the ends of the bottom rail may be connected to the lower ends of the meeting rail 10 and the outer rail 11 by any suitable fastening means, as at 18.

The light 14 may have a multiplicity of leaded panes of glass and a light may be held 85 in each frame by putty 19 or other fastening means.

The meeting rails 10 are constructed to afford a tongue and groove connection 20 when the frames are in a closed position, and a conventional form of pivoted latch 21 and a keeper 22 may be employed for retaining the frames closed.

Attached to the stiles 4, by screws 23 or other fastening means are vertically disposed 95 hook shaped strip members 24 that are adapted to be engaged by somewhat similar shaped complementary strip members 25, carried by the outer rails 11 of the door or window frames. The strip members 24 and 25 are 100

adapted to cooperate in forming a weather strip to exclude the elements from the interior of a compartment having the sliding door or window frames.

5 I attach considerable importance to the simplicity of construction and the fact that the doors or windows cannot become accidentally displaced and may be easily and quickly shifted for a desired adjustment.

10 One embodiment of my invention has been illustrated, but it is to be understood that the structural elements are susceptible to such variations and modifications as fall within the scope of the appended claims.

15 What I claim is:—

1. In a sliding door or window construction, top and bottom guide rails angular in cross section, frames slidable between said rails, said frames having an H-shaped top rail, the outer channel of said top rail being adapted to receive the top guide rail and the inner channel adapted to receive the upper edge of a light of glass, a sectional bottom rail consisting of two separate bars between which is received said bottom guide rail and the lower edge of said light, rollers supported by said bars and rollers engaging said lower guide rail.

2. In a sliding door or window construction, top and bottom guide rails angular in cross section, frames slidable between said guide rails, said frames having a sectional bottom rail comprising two plates adapted to be bolted together and rollers supported between said plates and thereby forming two channels, the lower channel being adapted to receive the lower guide rail and the rollers to contact therewith, a light of glass received at its lower edge in the opposite channel, an H-shaped top rail receiving the upper edge of said light and the upper guide rail.

3. In a sliding door or window construction, top and bottom rails angular in cross section, frames slidable between said guide rails, said frames having an H-shaped top rail, the outer channel of said top rail being adapted to receive said top guide rail and the inner channel adapted to receive the upper edge of a light of glass, a sectional bottom rail comprising two plates secured together to form inner and outer channels, rollers supported between said plates, the upper channel being adapted to receive the lower edge of the light of glass and the lower channel being adapted to receive the lower guide rail, said rollers contacting with said lower guide rail.

In testimony whereof I affix my signature.
AMABLE CHARLEBOIS.
